AUTOMATIC CONTROL FOR PHOTOGRAPHIC PRINTING EXPOSURES

Armand G. Denis, Rochester, N. Y., assignor to
 Eastman Kodak Company, Rochester, N. Y., a
 corporation of New York

Application April 23, 1931, Serial No. 532,159

9 Claims. (Cl. 95—75)

This invention relates to photography, and more particularly to photographic printing processes and apparatus of the automatic or semi-automatic types.

5 It has long been known that, when printing a series of negatives of different values of average transmission, as good or better average results are obtained if the intensity of the source of light used for printing is so adjusted that the product 10 of this (actinic) intensity and the average transmission remains constant, as when the exposures are determined by the judgment of experienced operators.

Attempts have been made towards developing 15 processes of printing in which the intensity of the source of light would be automatically adjusted so as to satisfy this relation, empirically found to be desirable.

In the past, these attempts have in the main 20 been directed to the use of a sensitive element for measuring the average transmission of the negative and to the use of methods in which each of the widely different readings of this element, corresponding to different values of the average 25 transmission of the negative, would bring about an adjustment of the light source intensity to a predetermined value calculated or empirically found to result in exact compensation for the given transmission.

30 In practice these methods have been far from satisfactory for the following reasons:

The measuring elements fail to follow rigidly defined response curves throughout wide ranges and differ individually from each other.

35 The lamps used as sources of light gradually vary in efficiency and differ from each other.

The characteristic response curves of a light sensitive element and a light source can be matched to each other, throughout the wide range 40 of variations of both which is necessary, only approximately and only by complicated circuits or methods.

The accuracy of control is affected and seriously disturbed by all accidental variations (such 45 as line voltage variation) and losses of adjustment or efficiency in the circuits or mechanical systems used to connect the measuring element and the source of light; in other words these methods are prone to loss of adjustment and are not inherently 50 self correcting or flexible.

It is an object of this invention to provide apparatus for the automatic regulation of the light source intensity in photographic printing, which is substantially free of the above faults and limitations; and to provide apparatus which will in-

stantaneously and automatically regulate the radiant energy level incident on the negative in such a manner that the radiant energy transmitted by the negative is maintained at a substantially constant level.

It is an object of this invention, in a photographic printer, to apply a radiation-sensitive measuring element to measure directly the radiant energy actually transmitted by the negative and incident on the positive, and to utilize this measurement to maintain substantially constant the radiant energy incident on the positive. In this respect this invention differs greatly from previous attempts in which the measuring element was applied to measure the average transmission of the negative; leading to a wide variation in the readings of the measuring instrument and requiring that the measuring element be operated through a large portion of its characteristic curve.

In this invention the measuring element is applied to measure a quantity which is, by the operation of the invention itself, maintained substantially constant; the measuring element therefore operates substantially at constant reading; and the shape of its response curve—which no longer needs to be matched to the characteristic curve of the source of light—becomes of no importance.

It is an object of this invention to provide methods and apparatus whereby the measuring element, while operating at substantially constant reading and allowing only negligible variations around a predetermined level of the radiant energy transmitted by the negative and incident on the positive, is able to control accurately and with negligible time lag large and sufficient changes in the intensity of the light source to compensate for widely different negative transmissions.

Another object of this invention is to provide a method and means for automatically controlling the printing of continuous film in such a manner that each successive frame of the positive copy shall receive a substantially identical amount of illumination irrespective of the density of the corresponding negative frame.

Another object of this invention is to provide a method and means for automatically controlling the photographic printing operation in such a manner that the total light transmitted by the negative is kept substantially constant.

Other objects and advantages of this invention will be apparent from the following description when read in connection with the accompanying drawings, and its scope will be pointed out in the appended claims.

Referring to the drawings, Fig. 1 shows in diagrammatic form an automatic printer circuit capable of carrying out this invention;

Fig. 2 illustrates the invention applied to a printer in which tungsten lamps are modulated for regulating the printing illumination;

Fig. 3 illustrates a simple manner in which the wattage of the tungsten lamps is indirectly controlled;

Fig. 4 shows one arrangement whereby the required relation may be achieved between the currents when two lamps are used in the lighting unit;

Fig. 5 is a schematic showing of means which may be used for advancing the film for printing;

Fig. 6 shows the invention as applied to a still printer; and

Fig. 7 illustrates an alternative arrangement for the control element.

In the printer circuit schematically shown in Fig. 1, a suitable glow discharge tube 10 is adapted to furnish printing illumination to a printing plane. Positioned behind the printing plane is a photo-electric cell 11 of any conventional type polarized by the batteries 12 and 13. In series with the cell 11 is a coupling resistance 14 which may conveniently be of the order of 20 megohms. The anode of the cell 11 is connected to the grid of the tube 15 and both the anode and the grid are connected with the resistance 14 and the battery 12 to ground. The filament of the tube 15 is connected directly to the ground so that the tube 15 is impressed with any variations in potential drop across the resistance 14. The tube 15 is at the input of an amplifying circuit of conventional design, the output of which is connected to the glow discharge tube 10. The filament heater windings and the power supply connections have been omitted as they are well understood.

The filament of the tube 15 at the input of the amplifier has a low thermal inertia and is fed raw 60 cycle alternating current which results, when the grid of this tube is at a suitable potential, in a 120 cycle oscillation being present in the output of this tube and appearing, greatly amplified, in the output of the amplifier, which feeds into the glow discharge tube 10 used as the source of printing illumination.

It will be seen that when radiant energy of varying intensity falls upon the cell 11, varying currents are passed by the cell and the potential drop across the resistance 14 varies in accordance therewith. Thus it will be seen that the grid of the tube 15 may be made to assume any potential, within wide limits, relatively to the potential of the filament.

It will further be clear to those familiar with amplifying circuits that there exists a well defined intensity of illumination falling upon the photocell 11 which will result in a normal bias of the grid of tube 15 and thus in operation of the amplifier at full amplification; that a small increase in the intensity of illumination would be sufficient to make the potential of the grid markedly negative to that of the filament and thus to cause the output of the amplifier to fall to a very low value; and that there exists a narrow range of intensities of illumination which may be termed the critical range, within which increases or decreases of the illumination small enough to be negligible in comparison with its absolute value will cause very large decreases or increases of the output of the amplifier.

In an actual printer, the photo-cell 11 and the

glow discharge tube 10 would be brought close together while the path of light between them would be restricted to the aperture of a printing gate; the arrangement being such that the light from the glow tube would be distributed evenly over this aperture, and collected on the surface of the photo-cell after passing through the film under process of printing at the gate.

The range of possible light intensities and the distance of the glow lamp from the gate would be so chosen as to suffice for correct printing, at the required speed, of negatives of the density range which it is desired to cover; while the sensitivity of the photo-cell 11 and its distance from the gate would be so adjusted that the amount of illumination reaching the printing surface will, when it is adequate for correct printing, also bring the grid of the tube 15 within the critical region.

It will be obvious that if these conditions are fulfilled, irrespective of the density of the negatives placed in the gate, the intensity of the glow lamp must instantaneously become adjusted so that the illumination falling upon the photo-cell 11 is that required to bring the grid of the tube 15 within the narrowly defined critical range, and which by adjustment, has been made equal to that adequate for correct printing; and the intensity of the glow lamp must remain at all times correctly adjusted, irrespective of the density of the negatives placed in the gate. For if the illumination falling upon the photo-cell 11 tended to decrease appreciably, the potential of the grid of the tube 15 would approach that of the filament, thus causing the glow lamp to approach its maximum illumination which, by definition, is more than sufficient with the most dense negative to bring the grid of the tube 15 within the critical range.

While if the illumination falling upon the photo-cell 11 tended to increase appreciably, the potential of the grid of the tube 15 would tend to become markedly negative to that of the filament, thus causing the glow lamp to approach its minimum of illumination which, by definition, is more than sufficient, with the least dense negative, to bring the grid of the tube 15 within the critical range.

In the control circuit above described it will be seen that the radiation sensitive element has been so placed and connected as to measure directly the radiant energy actually transmitted by the negative rather than the average transmission of the negative, although it does take into account such average transmission, along with several other factors such as the intensity of the printing source. The sensitive element 11 measures, in fact, the result of regulation, that is, the actual amount of printing illumination reaching the positive or a quantity rigidly proportional to it.

Then, by definition, if this actual amount is to be kept substantially constant, it will be seen that, in the operation of the device, the sensitive element 11 will be operated at substantially constant reading due to the fact that very small increases or decreases in the light incident on this sensitive element around a predetermined value results in very large changes in the intensity of the source of illumination 10.

In using the control circuit just described it is sufficient in order to obtain complete control to establish empirically the measuring level at which the amount of illumination reaching the positive film results in correct exposure and then

to connect the sensitive element with the variable source of light in such a manner and through such amplification that variations of the intensity of the source of illumination throughout its complete range and in the correct direction should result from variations of the reading of the sensitive element around its correct level sufficiently small to be negligible. From this it will be seen that the characteristic response curves of the sensitive element or of the source of illumination are of no importance and may be of any form. The characteristics of the amplifier connected to the tube are also unimportant and any reasonable variation of any of the elements involved is automatically corrected.

In applying the above described control circuit to a practical printer, it is necessary only to insure that each frame shall receive exposure for a definite time, either by providing a uniform rate of motion for the film or by some suitable shutter arrangement. One arrangement which may be used for advancing the film will be described in connection with Fig. 5. Given a definite time of exposure for each frame, it will be obvious that the above described circuit will instantaneously and automatically regulate the intensity of the printing illumination in such a manner that each successive frame of the positive copy in course of printing shall receive a substantially identical amount of illumination, irrespective of the density of the corresponding negative frame, the intensity of the printing source being varied frame by frame so as to compensate accurately for the variations in the average density of successive negative frames.

The circuit shown in Fig. 2 utilizes the same general method which has been described in connection with Fig. 1 and illustrates a form of automatic printer in which an ordinary tungsten lamp is used as the source of illumination and in which the wattage of the lamp is varied, in order to vary its illuminating intensity, through an electrical circuit free from moving parts and from appreciable time lag.

The use of a tungsten lamp as the source of illumination has several distinct advantages including easy replacement, smaller wattage for a given amount of illumination, wider range of variable actinic intensity without this range being limited by extinction or other discontinuous phenomena, and susceptibility to control by electrical methods involving no moving parts and free from appreciable time lag.

Although the tungsten lamp is a desirable and efficient source of light, there are two serious difficulties in using this type of lamp as a variable source of illumination for printing purposes, the first of these being that the wattages required to operate a tungsten lamp capable of giving adequate printing exposure at normal printer speed to the densest negatives which are liable to be encountered in practice are relatively large, and an amplifier capable of handling these wattages directly would be impractical both from the standpoint of size and cost. The second of these difficulties arises as the result of the large variation in spectral distribution of the tungsten light as the wattage and consequently the color temperature of the lamp are varied. It will be explained in the course of reference to Figs. 2 and 3, how these difficulties have been avoided.

Referring to Fig. 2, the photo-cell 11, sensitive to medium or long wave radiation, is positioned so as to effectively collect radiation from the source of illumination 10 transmitted through

the negative and positive films moved through the printing gate 16. The photo-cell 11 is polarized by the battery 12 placed in series with a coupling resistance 14 and so connected to the input circuit of the tube 17 that variations in the potential drop across the resistance 14, small enough to be negligible in comparison with the total drop across 12, are sufficient to vary the potential of the tube 17 through its critical range.

The tube 17 is preferably one known commercially as a 227 and is here used purely as a direct current amplifier. The plate of the tube 17 is connected to the cathode through the plate resistor 18 and the battery 19 so that the small variations of potential drop across the coupling resistance 14 are caused to result in large variations (of opposite kinds) of plate current in the tube 17, which variations are used to control a full wave rectifying circuit comprising two tubes 20 and 21 respectively.

The filaments of the tubes 20 and 21 are energized by a common alternating current transformer winding (not shown) and the plates are connected to the terminals of a center tap high voltage winding of a transformer 22. The filaments of the tubes and the center tap of the transformer 22 are connected through one winding of each of the chokes 23 and 24, and are intended to produce direct current saturation of the cores of said chokes. The filaments are connected to the plate of the tube 17 and the grids are connected together and given, by connection to a suitable tap on the battery 19, a permanent bias such that, when the photo-cell 11 is in darkness, the potential of the grid and filament of the tubes 21 and 20 substantially coincide and the rectified output to the chokes 23 and 24 is a maximum. The variable output of the tubes 20 and 21 is applied to cause a variable degree of saturation of the iron cores of the two chokes 23 and 24 which automatically varies the wattage supplied to the source of illumination 10 as hereinafter described.

The simple manner by which this variable D. C. output indirectly controls the variable wattage supplied to the tungsten light source 10 will be readily understood by reference to Fig. 3. The lamp 10 in series with an impedance consisting of the resistance 25 and the iron core inductance 23' in parallel is energized from a suitable constant voltage A. C. supply. The secondary winding of the choke 23 is connected to the variable D. C. output of the rectifying circuit, and the saturation of the iron core of the choke 23 is thus varied in accordance with the direct current flowing through the winding. Variation in the saturation of the iron core carries the inductance of the winding 23' through wide limits, and thus the current to the lamp 10 is varied through wide limits by relatively small current variations in the D. C. coil of the choke 23.

The percentage variations of inductance of the winding 23' possible by gradual saturation of the core are usually considerably more than sufficient to cause modulation of the lamp wattage through the range of illumination required in the printer. The resistance 25 usually permits of increasing appreciably the total amount of current handled by the circuit, and thus of using a lamp capable of higher wattage, without reducing the range of possible modulation below the limits required. A capacity, placed in parallel with the inductance 23', and of such value as to tune this inductance to the frequency of the source of supply under the condition of minimum saturation of the core,

145

150

may also be used to permit of greater efficiency.

The arrangement shown in Fig. 3 has been described merely to explain the general method used for indirectly controlling a tungsten light source.

- 5 It is not, in this simple form, suitable for use in an automatic printer, because of the variation in the spectral distribution which accompanies changes in the color temperature of the tungsten lamp. In a practical printer, it is preferable to 10 use a composite lighting unit which may well be made of two lamps as shown in Fig. 2, and in which the two lamps are simultaneously controlled in such a way that the total actinic radiation of the unit, and the radiation to which the 15 photo-cell 11 is sensitive, remain substantially proportional throughout their range of simultaneous variation.

If two lamps are so connected that their currents, throughout their range of variation, differ 20 by a substantially constant amount and if the light from these lamps is filtered so as substantially to exclude from the output of the "printing lamp" the radiations which might affect the photo-cell or other measuring element, and from 25 the output of the "control lamp" radiations which would affect the sensitive layer being printed, these two lamps may be combined in a unit, the combined output of which contains "printing light" and "measuring light" in unvarying proportions, and is therefore equivalent to a source 30 of radiant energy of constant spectral distribution.

In Fig. 4 is illustrated a circuit arrangement by which the required relation may be obtained 35 between the currents of the two lamps used in the lighting unit 10. The radiation from the lamp 27 in unit 10 is filtered by a red or yellow filter to remove all actinic radiations while passing the "measuring light"; and the radiation from 40 the lamp 28 is filtered by a blue or other suitable filter to free it from such wave lengths as would affect the photo-cell 11, while passing radiation suitable for printing purposes.

Both of the lamps 27 and 28 are placed in 45 series in a circuit identical to the one described in connection with Fig. 3 and in addition the lamp 27 and the resistance 25 are shunted by a fixed resistance 26; the choke 23, the inductance 23' and the resistance 25 performing the same 50 function as previously described.

The current passed by the lamp 28 divides 55 itself between the resistance 26 and the lamp 27 and its associated variable impedance circuit. The lamp 28 is preferably of a voltage low in comparison with the voltage drop 60 across the resistance 26 so that the voltage variations across the lamp 28 due to adjustment required for printing are negligible in comparison with the voltage drop 65 across the resistance 26; the current through the resistance 26 thus remains substantially 70 constant and independent of the variations of the system.

It will be seen that the current through the 75 lamp 28 exceeds by a substantially constant value the current through the lamp 27. Obviously the constants of the circuit can be so chosen or adjusted that the required proportionality may be obtained between the filtered "measuring" radiation of the lamp 27 and the filtered "actinic" 80 radiation of the lamp 28.

The arrangement shown in Fig. 2 differs from the one just described merely in that the lamp 28 is shunted by the resistance 29 in order to obtain the required constants of operation. The

complete arrangement shown in Fig. 2 includes a printing gate 16 through which negative and positive film are adapted to be intermittently moved and a shutter 16' adapted to exclude the printing light from the gate during said movement. Means for moving the film and operating the shutter are well known and, therefore, are not illustrated. When any one frame of the film is stationary in the gate 16 and the shutter 16' is open, radiation from the source 10 containing "actinic" and "measuring" radiation in unvarying proportion passes through the film and is collected by the photo-cell 11.

The response of the photo-cell 11, acting through the tube 17 and its associated circuit, 90 adjusts the intensity of the source 10 the proper amount to give the desired exposure in the known interval of time during which the shutter 16' is open.

The system just described is flexible and self-correcting and will always insure a definite amount of printing radiation to reach the positive film during the fixed time of the exposure. 95

It is to be understood that the described arrangement represents only one method by which the required constant relation between the simultaneously variable wattages of two or more lamps may be maintained. Any circuit including a plurality of lamps so connected and filtered that their respective wattages or currents are varied 100 simultaneously and remain, throughout the range required for printing, proportional to quantities differing by a fixed amount, and that their combined output, including actinic radiation and radiation suitable for measurement, remains in 110 unvarying proportion, independent of the variations of the system as a whole, is intended to fall within the scope of this invention.

In Fig. 6 the invention is shown applied to a printer or enlarger for "stills" comprising a 115 source of light 10 adapted to furnish printing light through a collecting lens 30, a negative 31, a projecting lens 32 and on to the positive 33 being printed. Suitably positioned between the negative 31 and the positive 33 is a partially reflecting and partially transmitting sheet 34, which may be of celluloid, or the like, for reflecting a portion of the light transmitted by the negative through a collecting lens 35 on to the photo-electric cell 11.

The partially reflecting surface of the member 34 reflects a known proportion of the illumination falling on the positive member 33 and this known proportion of the illumination is collected on the photo-electric cell 11 which controls the light source through a suitable amplifying circuit as described in connection with either Fig. 1 or Fig. 2. The response of the photo-electric cell 11 is utilized to vary the printing source of light 10 in such a way as to insure a definite level of radiant energy 135 always to be falling on the sensitive layer of the positive 33. Thus it will be seen that for any given time interval a definite amount of illumination will have reached the positive 33 and exposures can be accurately determined in advance. 140

In the arrangements so far described the radiations activating the photo-electric cell have been shown as emanating from the source utilized for furnishing the printing light. In Fig. 7 I have shown a modification which may be used for 145 printing either "stills" or motion picture film by the projection method in which a separate source of light is utilized in energizing the photo-electric cell in accordance with the transmission of the negative being printed. As shown in Fig. 7 a con- 150

densing lens 41 collects light from a source of radiation 10 and transmits this light through a negative 42 to the positive 43 being printed, through the medium of a suitable lens 44. As shown, a second glow discharge tube 40 is connected in series with the main discharge tube so as to vary in accordance with and simultaneously with the glow tube 10. The tube 40 is positioned to transmit light through the condenser 41, the negative 42, and on to the photo-electric cell 11 at an angle sufficient to prevent any of its rays reaching the positive film 43. In this arrangement no adjustment of the circuit needs to be made to compensate for varying thickness and opacity of the positive film being printed.

As heretofore described, the photo-electric cell 11 operates through a suitable amplifying circuit to control the variations of the source of printing light 10. It is obvious that the source 10 may comprise the tungsten source as described in connection with Fig. 2.

In Fig. 5 is illustrated one arrangement for advancing positive and negative film through a printing gate 16 suitable for use in connection with the circuit described in connection with Fig. 1. Although any standard arrangement may be used, the one illustrated comprises feed sprockets 50 driven by any suitable source of power, not shown, which are adapted to advance the negative film from the reel 51 and the positive film from the reel 52 at a uniform rate through the printing gate 16, after which the negative film is taken up on a suitable reel 53 and the exposed positive film is carried through any suitable developing tank 54. As described in connection with Fig. 1, the glow discharge tube 10 and the radiation sensitive element 11 are so connected that the glow lamp 10 is so modulated that the radiant energy reaching the positive film is always maintained at a constant level. With the negative and positive moving at a constant rate of speed, it will be seen that a uniform exposure is given for the entire positive film, regardless of any variations in density which may occur in the negative film.

While I have described in detail several ways of practicing my invention to comply with the requirements of the statutes I wish it understood that I do not intend to be limited to the exact methods or apparatus described inasmuch as in view of the disclosure obvious modifications will readily suggest themselves to those familiar with this art without departing from the spirit of my invention or the scope of the claims herein.

What I claim as new and desire to secure by Letters Patent of the United States is:

1. Photographic printing apparatus including a source of light, means for advancing a film of variable translucency between said light and a light sensitive element, means governed by the consequent activation of said element for varying the intensity of said light source and means associated with said source for causing said variation to occur without disturbing the spectral distribution of the light.

2. In photographic printing apparatus, an element sensitive to non-actinic light, means for directing a photographic record and a layer sensitive to actinic light in front of said element, a composite source of light for directing light through the record and layer and upon said element including two tungsten lamps, a non-actinic light transmitting filter associated with one of said lamps, an actinic light transmitting filter associated with the other of said lamps and means controlled by the response of said sen-

sitive element for varying the intensity of said lamps, said lamps being so connected that throughout the range of variation the actinic radiation of one bears a constant ratio to the non-actinic radiation of the other.

3. In the art of photographic printing the method of automatically maintaining a printing light of constant intensity falling on a sensitized layer being printed which comprises passing a composite beam of radiant energy through a photographic record and the sensitized layer, causing the non-actinic component of the beam to produce a current varying with the translucency of the record, and utilizing said varying current to modulate said composite beam without disturbing its spectral distribution.

4. In the art of photographic printing the method of controlling the actinic radiation falling on a sensitized layer being printed which comprises passing non-actinic radiation through the photographic record being printed, modulating said non-actinic radiation in accordance with the translucency of the record and simultaneously modulating the actinic radiation to maintain it in unvarying proportion with the non-actinic radiation.

5. Photographic printing apparatus including means for holding superposed negative and positive films in an exposure window, a composite source of light in front of the window including a source filtered to transmit actinic light and a source filtered to transmit non-actinic light, a light sensitive element behind said window adapted to be activated in accordance with the non-actinic light impinging thereon and means controlled by said element for varying simultaneously the two components of said composite source of light.

6. Photographic apparatus of the variable intensity constant time type comprising a source of light for illuminating a printing window, means for uniformly advancing a photographic record and a sensitized layer past said window, an amplifier tube having a control electrode and an output circuit, means for varying a potential on the control electrode in accordance with the intensity of the light transmitted by said record at said window and means controlled by the output circuit for varying the intensity of the light falling on the printing window, the complete arrangement forming a photo-electric governor operative to maintain substantially constant at a predetermined value the potential on said control electrode, whereby the printing light falling on said layer is of a predetermined intensity.

7. Photographic printing apparatus for controlling the intensity of an exposure given a sensitized layer through a photographic record of varying translucency, comprising a source of light for furnishing the exposing light, means for varying the intensity of the light falling on the record, amplifying means for controlling said light varying means and a light sensitive element for regulating the input to said amplifying means in accordance with the intensity of the exposing light transmitted by said record whereby negligibly small variations in the intensity of the exposing light results in large variations in the intensity of the light falling on said record.

8. In photographic printing apparatus, a source of light for exposing a sensitive layer through an image bearing record, means for varying the intensity of the light source in accordance with the light falling on said layer including a light sensitive element for varying a current in a

circuit as a function of the intensity of the light falling on said layer, a resistance in the circuit for translating the varying current into a varying potential, a source of electrical energy, 5 an amplifier connected between said source of energy and said source of light, a control element subjected to said varying potential for regulating the gain of said amplifier, whereby the intensity of the light source varies through wide 10 limits upon relatively small variations in potential drop across said resistance.

9. In photographic printing apparatus, a source of light for exposing a sensitive layer through an image bearing record, means for

16

varying the intensity of the light source in accordance with the light falling on said layer including a light sensitive element for varying a current in a circuit as a function of the intensity of the light falling on said layer, a resistance in 80 the circuit for translating the varying current into a varying potential and amplifying means controlled by the varying potential for regulating the energy input to said light source, whereby the intensity of the light source varies through 85 wide limits upon relatively small variations in potential drop across said resistance.
